UNITED STATES PATENT OFFICE.

MAXIMILIEN BEAUDOIN, OF MONTREAL, QUEBEC, CANADA.

DESIGN FOR A COMBINED GRAMOPHONE AND RADIOCABINET.

Application filed August 12, 1926. Serial No. 18,707. Term of patent 3½ years.

To all whom it may concern:

Be it known that I, MAXIMILIEN BEAUDOIN, a subject of the King of Great Britain, residing at 1679 Plessis St., city of Montreal, Province of Quebec, Canada, have invented a new, original, and ornamental Design for a Combined Gramophone and Radiocabinet, of which the following is a specification, reference being had to the accompanying drawing, forming part thereof.

The figure is a perspective view of the combined gramophone and radiocabinet, showing my new design.

I claim:

The ornamental design for a combined gramophone and radiocabinet, as shown.

MAXIMILIEN BEAUDOIN.
